NONREFILLABLE CONTAINER

Luis Ferrer Maríño, Vigo, Spain

Application December 20, 1941, Serial No. 423,730
In Spain January 15, 1941

4 Claims. (Cl. 215—25)

It is unnecessary to elaborate on the importance of finding a practical solution to the problem of providing bottles with a device for preventing tampering with the contents or refilling the bottles, I proceed to describe what the device of this invention comprises, with the assistance of the accompanying drawing forming part hereof.

The device consists essentially of the parts which are described as a preferred form or embodiment, since without fundamentally varying any of them, they may undergo certain modifications which do not affect the essence of the ensemble. The material to be used in its construction may be the one suitable for each purpose.

In the attached drawing, Fig. I is a sectional view, which represents the device as a whole, arranged in the neck of a bottle or the like. The other figures represent different separated portions of the unit, to wit:

Fig. II discloses a cap ring with pendent retaining clamps attached thereto.

Fig. III is an elevation of a rectangular plate of the device.

Fig. IV is an elevation of a similar plate forming a valve closure for a passage through said device.

Fig. V illustrates a spherical counterweight.

Fig. VI shows the form of a triangular prismatic float of the device.

Fig. VII illustrates a hollow cylindrical member of the same device.

Fig. VIII is a ring gasket for the same, while Fig. IX illustrates a group of parts of said device including a ring or washer, an intermediate valve member and a lower ring member.

Throughout, the same references indicate the same or like parts.

As may be noted in Fig. I, the hollow cylindrical member 2 is surrounded by a ring gasket 1 fitting tightly against the inner surface of the neck 13 of the container while a loose flat valve closure plate 3 is adapted to close the orifice in member 2. Above the closure plates is a prismatic float 4 comprising a straight prism, of parafined cork for example, having an equilateral triangular base as shown in Figure VI. 5 represents a spherical weight retained in the neck 13 of the bottle or container by a ring member 6 having a plurality of spaced downwardly projecting or pendent portions a (Fig. IX) formed with lower conical seats for seating or receiving the spherical member 5 therein. The aperture in ring member 6 is normally closed by valve 7 when the container is upright and is retained assembled with the container by means of a washer or ring 9 held in place by a pair of clamping straps 8, which are retained in place by an end or cap ring 11 and a gasket 12 fitting within the lip of the neck 13.

Operation.—From the vertical position of the container to the inclined position in a course of about one hundred and ten degrees, by the action of the spherical body 5 on the float 4 and from 5 this to the value 3, the passage of the body 2 remains hermetically closed, it being impossible to introduce liquids in the container. When the container is inclined to an extent of one hundred and eighty degrees, if liquid is introduced 10 through the neck of the container it will act on the float 4 to cause it to exert pressure on the valve 3, shutting passageway of 2, as above. Thus provided it is not deemed preferable to dispense with part 3, causing this shutting function to be 15 performed by the float itself.

In order to empty the container, all that is necessary is to place it in the last named position, i. e., between degrees one hundred and eighty and one hundred and ten, starting from 20 the original vertical position, whereby, being displaced by their own gravity and that of the liquid, the moving parts 3, 4, 5 and 7, the liquid flows freely out.

Any attempt at interfering with the function 25 of the closure members is thus rendered impossible by the rectangular baffle plate 10 and the valve-shaped device formed by the ring member 6 and valve 7.

Having made the foregoing description I will 30 add that the invention rests on the following claims:

1. In an automatic device for preventing tampering with the contents of a bottle, having a neck and a spherical weight in the neck, the combination of a bottle a prismatic float beneath the spherical weight, a perforate member below said float, a gasket tightly fitting the neck of the bottle and retaining said perforate member in place, a loose flat plate forming a valve closure disposed between said float and said perforate member, a ring member spaced above said prismatic float having downwardly projecting spaced portions forming a seat for receiving said weight and retaining the same in the neck, 40 a cap ring, a cap-ring securing gasket, a plurality of downwardly extending strap members attached to said cap ring for retaining aforesaid ring member in place, a movable valve above the opening in the latter, and a perforate 45 retaining member secured in place by said strap members above said movable valve to prevent loss of the same from the device.

2. A device according to claim 1, wherein the prismatic float is triangular in shape when seen 50 from above.

3. A device according to claim 1, wherein the perforate retaining member is a washer with a central opening therein.

4. A device according to claim 1, wherein the 60 perforate member is a hollow short cylinder.

LUIS FERRER MARÍÑO.
